DOUBLE-BREASTED GARMENT

Thomas Turunen, Detroit, Mich.

Application April 24, 1939, Serial No. 269,804

3 Claims. (Cl. 2—96)

This invention relates generally to improvements in wearing apparel and refers more particularly to a novel double-breasted garment, such as a coat.

5 It is one of the principal objects of this invention to provide a double-breasted garment affording a greater freedom of movement of the wearer and having a distinctive pleasing appearance.

Another advantageous feature of this invention resides in the provision of a double-breasted garment rendering it possible to contour the front portion of the garment to fit a variety of shapes and to compensate for peculiarities that often times prohibit proper tailoring of the garment.

15 The foregoing, as well as other objects, will be made more apparent as this description proceeds, especially when considered in connection with the accompanying drawing, wherein:

Figure 1 is a fragmentary front elevational view 20 of a coat embodying my invention; and

Figure 2 is an elevational view showing the coat in another position.

Double-breasted coats have been one accepted style of coat for many years and are distinguished 25 principally from single-breasted coats in that the free edge portions overlap each other for a substantial distance at the front of the wearer forming a double thickness of material in this region. This particular type of coat front not only hinders freedom of movement of the wearer, but is not conducive to tailoring the garment so that it will hang properly on all of the various 30 different shapes of individuals.

According to this invention, the above objections 35 are overcome without appreciably altering the appearance of the double-breasted style by forming the garment in the manner clearly illustrated in the drawing. In detail, it will be noted that the lower regions of the overlapping flaps 10 40 of the coat are cut away, as at 11, to such an extent that when the flaps are buttoned in overlapping relationship, the free edges 12 assume a

position on the vertical center line of the garment in juxtaposition to each other. In other words, when the garment is buttoned in the manner shown in Figure 1, a slit is formed at the center of the garment, with the result that a freedom 5 of movement is provided comparable to a single-breasted garment.

Upon reference to Figure 2, it will be noted that the flaps 10 are also slit, as at 13, in substantial alignment with the edges 12, and the edges of 10 the slits 13 are sewed together. The purpose of this arrangement is to permit cutting and fitting the garment opposite the stomach of the wearer so as to compensate for protrusions or irregularities 15 in this region of the wearer's body. 15

What I claim as my invention is:

1. A double-breasted garment with overlapping flaps at the front side having portions adapted to be buttoned in overlapping relation and having edges extending below the buttoned portions of 20 the flaps offset from the free edges of the buttoned portions of said flaps a distance predetermined to provide a slit on the vertical center line of the garment at the front side of the latter.

2. A double-breasted garment having overlapping flaps at the front side of the garment and having the lower portions of the flaps cut away to such an extent that the free vertical edges of 25 said portions meet substantially on the vertical center line of the garment. 30

3. A double-breasted garment with overlapping flaps at the front side having portions adapted to be buttoned in overlapping relation and having edges extending below the buttoned portions of the flaps offset from the free edges of the buttoned portions of said flaps a distance predetermined to provide a slit on the vertical center line 35 of the garment at the front side of the latter, and seams extending upwardly from the offset edges aforesaid a sufficient distance to provide for fitting 40 the front portions of the garment.

THOMAS TURUNEN.
